UNITED STATES PATENT OFFICE.

JOHN GRIESHAMER, OF JACKSONVILLE, FLORIDA.

AUTOMOBILE-LIGHT DIMMER.

1,353,231.

Specification of Letters Patent. Patented Sept. 21, 1920.

Application filed December 6, 1916. Serial No. 135,443.

To all whom it may concern:

Be it known that I, JOHN GRIESHAMER, a subject of the Emperor of Germany, residing at Jacksonville, in the county of Duval 5 and State of Florida, have invented certain new and useful Improvements in Automobile-Light Dimmers; and I do hereby declare the following to be a full, clear, and exact description of the invention, such as 10 will enable others skilled in the art to which it appertains to make and use the same.

This invention relates to new and useful improvements in headlight constructions and has for its primary object the provision 15 of a body and reflector construction that will deflect the largest proportion of the rays of light toward the ground to prevent blinding of approaching traffic and the loss of light which does not strike the ground, but still 20 will permit a small amount of light to shine straight ahead or in a horizontal plane to moderately illuminate objects in the roadway at a distance and render comparatively safe driving at night time.

25 Another object of this invention is the provision of means for establishing a connection between the reflector and body at their front ends which firmly supports the reflector and is also coöperated with by the 30 lens supporting door when in a closed position to prevent any relative movement of the reflector and the lens.

A still further object of this invention is 35 the provision of a headlight construction of the above stated character, which shall be simple, durable and efficient, and which may be manufactured and sold at a comparatively low cost.

With these and other objects in view as 40 will become more apparent as the description proceeds, the invention consists of certain novel features of construction, combination and arrangement of parts as will be hereinafter more fully described and 45 claimed.

For a complete understanding of my invention, reference will be had to the following description and accompanying drawing, in which:

50 Figure 1 is a top plan view of a headlight construction constructed in accordance with my invention;

Fig. 2 is a vertical sectional view of the same.

55 Referring in detail to the drawing, the numeral 1 indicates the body of the lamp hav-

ing oppositely disposed ears 2 for receiving the ordinary lamp supporting standards of an automobile. Located within the body 1 is a suitable reflector 3 which has formed in 60 the rear wall thereof a socket 4 for receiving an electric lamp 5. The rear wall of the body 1 is provided with an opening in communication with the socket 4 to permit an electric terminal to be inserted therein. 65 The forward edges of the body 1 are bent inwardly to form an annular flange 6 over which the edges of the reflector 3 are bent as illustrated at 7 to securely hold the reflector 3 within the body 1. A suitable door 70 8 is secured to the body 1 as illustrated at 9 and carries a lens 10 which bears against the edges of the reflector 3. The upward end of the body 1 is cut away in the direction of its lower end so as to permit the rays of light from the electric lamp 5 to shine directly downwardly upon the ground in front of the lamp. An electric lamp 11 is mounted within the bottom of the reflector 3 and body 1 and is of a smaller size than the electric lamp 5 to provide a pilot light to be used when the lamp is employed in cities or illuminated places.

A substantially arch-shaped hood 12 has formed thereon a flange 13 which is bolted 85 or otherwise secured to the door 8 as illustrated at 14. The hood 12 is provided with an opening 15 to receive a set screw 16 which extends through an elongated slot 17 in an extension hood 18 whereby the extension hood 18 is adjustably secured to the hood 12. In operation, when the rays of light from the electric lamp 5 are reflected from the body by the reflector 3, the upper portion of the rays will shine against the hoods 12 and 18 and be directed downwardly upon the ground, thus preventing the rays of light from shining in the eyes of approaching traffic. By releasing the tension of the set screw 16, the length of the hoods 18 and 12 may be adjusted so as to regulate the amount of light to shine directly ahead of the lamp.

While I have shown and described the preferred embodiment of my invention, it will be understood that minor changes in construction, combination and arrangement of parts may be made without departing from the spirit and scope of the invention as claimed.

Having thus described my invention, what I claim is:

A headlight comprising a substantially tubular shaped body and reflector, one fitting within the other and each being tapered to provide large and small front and rear ends respectively, concaved rear walls closing the rear ends of the body and reflector, an electric lamp socket formed in the upper portion of the rear wall of the reflector to receive an electric lamp to support the same adjacent to the highest point of said reflector and said socket abutting the rear wall of the body to aid in supporting the reflector therein, said body and reflector having their large forward ends disposed on a downwardly inclined plane to provide the great-

est reflected surface of the reflector uppermost and to permit the largest proportion of rays of light to escape in a downwardly and forwardly direction, means securing the reflector to the body so as to support 20 said reflector within the body and in spaced relation thereto, and a hood carried by the body and extending to a point in a plane below the electric light.

In testimony whereof I affix my signature 25 in presence of two witnesses.

JOHN GRIESEHAMER.
